CLAIM

The ornamental design for a front bumper end cap for a vehicle, as shown and described.

DESCRIPTION

This application contains subject matter related to the following co-pending U.S. design patent application: Application Ser. No. 29/572,848, filed herewith and entitled "Truck Cab, Toy, and/or Replicas Thereof".

FIG. 1 is a left, front perspective view of a first embodiment of a front bumper end cap for a vehicle according to the design;

FIG. 2 is a front view thereof;

FIG. 3 is a right side view thereof; and

FIG. 4 is a top view thereof.

FIG. 5 is a right, front perspective view of a second embodiment of the front bumper end cap for a vehicle according to the design;

FIG. 6 is a front view thereof;

FIG. 7 is a left side view thereof; and

FIG. 8 is a top view thereof; and

FIG. 9 is a perspective view of a possible environment of the first and second embodiments.

The broken lines depict environmental structures that form no part of the claimed design.
